UNITED STATES PATENT OFFICE.

AARON TOWNSEND SENECAL, OF ROCK ISLAND, ILLINOIS.

DOOR-CONTROLLING DEVICE FOR TRAPS.

Application filed December 27, 1926. Serial No. 157,264.

The object of this invention is to provide a fitting or attachment which may be sold as an article of manufacture and which may be immediately attached to any suitable box, for 5 the purpose of converting the latter into a box trap.

A further object is to provide a frame adapted to be attached to the side or end of a box in which an opening has been cut, 10 this frame mounting a sliding door or gate, and being adapted to mount a combined door retaining and releasing device and a bait mounting element, making it possible to construct the complete trap from any 15 suitable box, in a very few minutes, and without expert work of any description.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a view of the trap in vertical longitudinal section.

Figure 2 is a perspective view of the door frame, constituting a part of the attachment, 30 which together with the elements of Figures 3 and 4 will constitute the article of manufacture as it is to be placed on the market, independently of the box.

Figure 3 is a perspective view of the door 35 or gate,

Figure 4 is a perspective view showing a plate to be hung on the inner side of the door frame, the lower offset pin, or projecting end of the wire, forming a trip for the 40 door, and the longer portion of the wire forming a part of the bait retaining device of Figure 1.

As already indicated, any suitable box may be employed, and the attachment as sold is 45 to be applied to the box by merely cutting an opening 10 in the front wall 11 of the box. The top of the box is designated 12, the end which is left intact is shown at 13, and the bottom of the box is designated 14.

50 The elements of Figures 2, 3 and 4, constitute the article of manufacture as it is to be sold, and the door frame includes a main wall or board 15 on which are mounted channelled guides 16 and 17, the opposite 55 side of the board carrying if desired, trans-

versely extending elements such as 18 and 19, at the ends thereof. Within the element 15 an opening is cut and this opening may be of circular form if desired, as shown at 20, a cutaway portion being provided at 21 beyond the limits defined by the circular edge portion of the opening. A pin or stop 22 limits the downward movement of the door.

The opening 20 in the door frame, and consequently the opening 10 in the box structure, is to be closed by means of a door or gate 25, which may be of circular configuration, and which carries a central pin 26 by means of which it may be raised manually.

On the inner side of the door frame, which is secured to the front wall of the box by securing devices 27, I mount a door retaining and releasing device and a bait holding device, the major portion of which is shown in Figure 4. A plate 28 is provided with an opening or key hole slot 29 for engagement with a pin 30 on the inner side of the element 15 of the frame. A heavy wire or the like designated 31 is provided with a pointed end portion 32 on which the bait is to be mounted, and a collar or the like 33 prevents the bait from being forced too far along the wire. This wire forming a part of member 31 is deflected at 34, and is again deflected to form the pin or door retaining device 35. The portion 34 is secured to the plate 28 by soldering, or otherwise, and the element 35 projects from one surface of plate 28, and the remainder of the structure projects from the other side, as shown in Figure 4.

When the device of Figure 4, shown in complete form in Figure 1, is properly set 95 so that it will be engaged by the door 25, the lower end or edge of which rests on the portion 35, and when bait is applied at 32, an extremely slight movement of the strip thus provided will cause the movement of 100 plate 28, loosely suspended from pin 30, and this movement will release the door 25, allowing it to fall by gravity. The element 31 with the trip 35 as a part thereof, will also drop slightly (after the element 35 has 105 been released), and this element will then pass across the upper edge of the door and act as a locking device.

It will be observed that the successful operation of the attachment or fitting depends 110

upon the sensitiveness of the door and trip. The shape of the door is such that no binding action can occur under any circumstances, and the construction of the retaining and releasing elements is such that there can seldom if ever be any failure to act promptly and effectively.

Having described the invention what is claimed is:—

- 10 1. A door and door operating device for traps, comprising a frame having an opening therein, a slideable door for closing the opening, a detachable plate mounted for rocking movement with reference to the inner side of the door frame, and a combined bait holder and door releasing and locking device carried by the plate.
- 15 2. A door and door operating device for traps, comprising a frame having an opening therein, said frame being adapted to be

mounted on the cutaway wall of a box, a circular sliding door mounted in the frame for closing the opening and cutaway portion, a plate mounted for movement with reference to the inner side of the door frame, 25 and a combined bait holder and door retaining and releasing device carried by the plate.

3. A door and door operating device for traps, comprising a frame having an opening therein, said frame including guide-ways, a circular sliding door mounted for movement in the guide-ways, a plate mounted for movement with reference to the inner side of the door frame, and a bait holder 30 and door releasing and locking device carried by the plate.

In testimony whereof I affix my signature.

AARON TOWNSEND SENEICAL.
